(57) **CLAIM**

The ornamental design for a trapezoidal link, as shown and described.

DESCRIPTION

FIG. 1 is a perspective view of a trapezoidal link;

FIG. 2 is a front elevation view thereof; the rear elevation view being a mirror image thereof;

FIG. 3 is a left elevation view thereof; the right elevation view being an identical image thereof; and,

FIG. 4 is a top plan view thereof; the bottom elevation view being an identical image thereof.
